UNITED STATES PATENT OFFICE.

WILLIAM CARRICK, OF BOSTON, MASSACHUSETTS.

SASH-FASTENER.

SPECIFICATION forming part of Letters Patent No. 694,612, dated March 4, 1902.

Application filed May 20, 1901. Serial No. 61,002. (No model.)

To all whom it may concern:

Be it known that I, WILLIAM CARRICK, of Boston, in the county of Suffolk and State of Massachusetts, have invented certain new 5 and useful Improvements in Sash-Fasteners, of which the following is a specification.

This invention has for its object to provide a cam-shaped sash-fastener adapted to automatically engage a window-sash and prevent 10 the same from moving either upwardly or downwardly and also adapted to be retracted to an inoperative position to permit the unobstructed movement of the sash intended to be held by the fastener or of the sash on which 15 the fastener is supported.

The invention consists in the improvements which I will now proceed to describe and claim.

Of the accompanying drawings, forming a part of this specification, Figure 1 represents a transverse section through the meeting-rails of two of the sashes of a window, showing a fastener embodying my invention supported by the lower sash and adapted to engage the 25 upper sash. Fig. 2 is an elevation of the same from the inner side of the window. Fig. 3 is a section on line 3 3 of Fig. 2. Fig. 4 is a view similar to a portion of Fig. 1, showing a different adjustment of the fastener. Fig. 30 5 represents a view similar to Fig. 3, showing the fastener retracted and held in an inoperative position. Fig. 6 represents a section on line 6 6 of Figs. 5 and 8. Fig. 7 represents a section on line 7 7 of Fig. 3. Fig. 8 represents a top plan view showing the fastener held in the position shown in Fig. 5. Fig. 9 represents, in two views, a section on line 9 9 of Fig. 5. Fig. 10 represents a perspective view of the button-retracting device herein- 40 after referred to.

The same reference characters indicate the same parts in all the figures.

In the drawings, *a* represents a support, which is here shown as a bracket adapted for 45 attachment to the meeting-rail *b* of the lower sash of a window. *c* represents a stud affixed to said support.

d represents a button, which is provided with a slot *d'*, through which the stud *c* passes, 50 said slot being formed to permit the button both to oscillate on the stud and to move edgewise toward and from one of the side rails

of the upper sash *e*. The button has a cam-shaped or eccentric face *d²*, which is eccentric to the stud *c* in any position that the button can assume on the stud and is arranged to bear against the side rail of the upper sash. 55

f represents a spring interposed between the stud *c* and the bottom of a cavity formed for the reception of the spring in the button *d*, said spring tending to force the cam-face *d²* yieldingly toward the part of the upper sash on which it bears. It will be seen, therefore, that when the spring *f* is free to act it holds the cam-face of the button yieldingly 65 in engagement with the upper sash, whether the button be in the position shown in Figs. 1, 2, and 3 or that shown in Fig. 4 or in an intermediate position. Hence the button is always in a position to act to prevent move- 70 ment of either sash relatively to the other, the button preventing upward movement of the lower sash and downward movement of the upper sash when in the position shown in Fig. 1 and preventing downward movement 75 of the lower sash and upward movement of the upper sash when in the position shown in Fig. 4.

The button is provided with a suitable handle or projection on the side of the stud *c* opposite the cam-face *d²*, whereby the operator may grasp the button and retract it, thus withdrawing the cam-face from contact with the upper sash when it is desired to quickly adjust either sash. In the present case the 80 handle or projection is an extension *d³* of the body of the button, said extension having curved sides *d⁴ d⁴*, whereby it may be conveniently grasped.

I prefer to provide the button with means 90 whereby it may be locked or secured in a retracted position, so that when it is adjusted to the intermediate position shown in Fig. 5 it will be held out of contact with the upper sash. Any suitable device may be employed 95 for this purpose. The retracting device here shown is a stem *g*, journaled in a socket formed for its reception in the extension of the button and having its inner end slotted to form arms or bifurcations *g' g'*, separated by a slot 100 of greater width than the diameter of the stud *c*, so that when the stem *g* is in the position shown in Figs. 3, 4, and 7 its arms *g'* will be free to move lengthwise across the stud *c*, so that

the stem does not affect the freedom of edge-wise movement of the button. The inner ends of the arms g' have concave or cam-shaped faces g^2 , which are adapted when the stem is given a quarter-turn to the position shown in Figs. 5 and 6 to engage one side of the stud c , and thus force the button backwardly and hold it in the retracted position shown in the figures last mentioned. The stem g is prevented from moving endwise independently in the button by means of a key or pin h engaging a peripheral groove i in the stem. The stem is preferably provided with a thumb-piece or handle g^3 , whereby it may be conveniently rotated from one of the positions described to the other.

I do not limit myself to the form and construction of the device herein shown and claimed, as the said form and construction may be variously modified without departing from the spirit of my invention. In particular the holder a may be formed for application to any other suitable support, such as the casing of the window, instead of being adapted for attachment to the meeting-rail of the lower sash.

It will be seen that the spring pressing the cam-face of the button against the upper sash prevents rattling of either sash.

The cam-face of the button may have a facing or coating of rubber or other suitable yielding material to prevent the button from indenting the sash on which it bears. The inner edge of said facing is indicated by the dotted line m in Fig. 4.

I claim—

1. A sash-fastener comprising a holder hav-

ing a stud or journal, and a button having a cam-face, a journal-receiving slot whereby the button is adapted both to oscillate and move edgewise on said journal, a spring whereby the cam-face is pressed yieldingly from the journal to automatically bind if oscillated in either direction, and means for locking the button in retracted and inoperative position. 45

2. A sash-fastener comprising a holder having a stud or journal, and a button having a cam-face, a journal-receiving slot whereby the button is adapted both to oscillate and move edgewise on said journal, and a spring whereby the cam-face is pressed yieldingly from the journal, said button having a handle or projection at the opposite side of the journal from the cam-face, whereby the button may be retracted against the force of the spring, to make 55 its cam-face inoperative.

3. A sash-fastener comprising a holder having a stud or journal, a button having a cam-face, a journal-receiving slot whereby the button is adapted both to oscillate and to move 60 edgewise on said journal, a spring interposed between the journal and the cam-face of the button, and a button-retracting stem journaled in the button and having a cam-shaped inner end bearing on said journal, said stud 65 being prevented from moving endwise in the button.

In testimony whereof I have affixed my signature in presence of two witnesses.

WILLIAM CARRICK.
